(Cl. D34—15)

To all whom it may concern:

Be it known that I, Harold G. Arnold, a citizen of the United States, residing at 1201 Forest Drive, Wooster, Ohio, in the county of Wayne and State of Ohio, have invented a new, original, and ornamental Design for a Roly-Poly Toy, of which the following is a specification, reference being had to the accompanying drawing, forming part thereof.

Fig. 1 is a top plan view of a roly-poly toy.

Fig. 2 is an end view with parts broken away.

Fig. 3 is a perspective view, showing my new design.

I claim:

The ornamental design for a roly-poly toy, as shown.

HAROLD G. ARNOLD.
